(57) **CLAIM**

The ornamental design for a chair, as shown and described.

DESCRIPTION

FIG. 1 is a left front perspective view of a chair, showing my new design;

FIG. 2 is an elevational view of the left side, thereof;

FIG. 3 is a top plan view, thereof;

FIG. 4 is a front elevational view, thereof;

FIG. 5 is a rear elevational view, thereof;

FIG. 6 is an elevational view of the right side, thereof;

FIG. 7 is a bottom plan view, thereof; and,

FIG. 8 is a perspective view taken from an elevated position,

showing the arm compartment covers in alternative open position, the broken-line representation of the video monitor, mount, and keyboard being included solely for illustrative purposes, forming no part of the claimed design.
